DISPENSING RECEPTACLE

Frank J. Venning, Cleveland Heights, and Frank J. Yeip, Euclid, Ohio, assignors to The Union Salt Company, Cleveland, Ohio, a corporation of Ohio

Application July 18, 1935, Serial No. 32,002

10 Claims. (Cl. 229—17)

This invention relates to a dispensing receptacle or container which is adapted to contain granular material of such character that it may be poured from the receptacle and which is provided with a spout formed of the same material as the receptacle, which spout is normally folded within the container.

One of the main objects of the invention is to provide a dispensing container of the character described which is provided with a pouring spout which is disposed at the intersection of the top and a side wall of the container and which is readily accessible so as to be moved to the pouring position.

15 A further object of the invention is to provide a multi-sided container which may be formed from a single piece of material and which has a spout formed in one side wall thereof and integral therewith and movable to a pouring position together with a flap which forms a part of the top wall of the container and which has a tab portion overlying the spout and a second flap which overlies the first flap and is provided with a reinforcing tab which overlies the first mentioned tab and tends to urge the same downwardly toward the spout, the purpose of which will hereinafter more fully appear.

20 A further object of the invention is to provide a carton of the character described which may be formed from a single piece of material and which has a pouring spout in one wall of the container which is readily accessible and which has a cut-away portion to provide access to the spout, the container being provided with a label which 25 covers such opening and which is not sealed to the wall of the container opposite the spout and which is also provided with an extension or tab which projects slightly beyond the plane of the spout when the spout is in non-pouring position and which may be lifted up to facilitate access 30 to the spout, which tab also functions to hold the spout both in the pouring and non-pouring position.

25 Further and more limited objects of the invention will appear as the description proceeds and by reference to the accompanying drawings in which Fig. 1 is a fragmentary perspective view of our improved container with the label thereon; Fig. 2 is a fragmentary perspective view with the label removed to show the details of construction; Fig. 3 is a fragmentary perspective view similar to Fig. 2 with the spout in the pouring position; Fig. 4 is a view in front elevation of a container shown in Fig. 2; Fig. 5 is a top plan view of the same container; Fig. 6 is a fragmentary sectional

view on the line 6—6 of Fig. 5; Fig. 7 is a vertical sectional view on the line 7—7 of Fig. 4; Fig. 8 is a view similar to Fig. 7 with the spout in the pouring position; and Fig. 9 is a plan view of the blank from which the container is formed. 5

Referring now to the drawings, the reference character A designates generally the container as well as the blank from which the container is formed and which is preferably formed of paper, cardboard or similar material. The blank, when 10 folded, provides a container which is made up of a plurality of side walls designated by the reference characters 1, 2, 3, 4 and 5. The walls 3 and 5 overlie each other and are secured together preferably by means of glue, paste or suitable 15 cement. Each of the walls 1, 2, 4 and 5 is provided at the end thereof with flaps 1^a, 2^a, 4^a and 5^a which are folded to form the bottom of the container. The wall 1 is provided at its opposite side with a flap 1^b and the wall 2 has at one end 20 thereof a flap 2^b. The wall 3 is provided at one end with a spout-forming portion 7 which is scored or cut, as shown by the dotted lines indicated by the reference character 8 to provide a pair of parallel side walls. The wall 4 is provided with a flap 4^b disposed opposite the flap 4^a. The wall 5 is provided with a flap 5^b which is disposed opposite the flap 5^a. The flap 5^b is the innermost flap when the carton is formed and is provided with a rectangular tab portion 9 cut 25 through along three sides thereof. Disposed opposite the tab 9 and in the side wall 5^a is a rectangular cut-out or opening 10. It is to be noted that the tab portion 9 projects a slight distance beyond the fold in the side wall 5, the purpose 30 of which will hereinafter appear. The flap 2^b is provided with a cut-out portion 11 disposed immediately adjacent the flap 5^b and which when the carton is formed provides an opening which is disposed immediately over the tab 9. The flap 40 1^b is provided at one side thereof with a cut-out which forms a reinforcing tab or projection 12 which, when the container is formed, is disposed immediately over the tab 9. 35

When the container is formed, the flap 5^b is 45 the innermost flap and is disposed over and contiguous to the spout 7 forming a part of the side wall 3 of the container. The flap 1^b overlies and engages the flap 5^b with the reinforcing tab 12 thereof disposed immediately opposite and in 50 engagement with the tab 9. The next flap is the flap 2^b which is folded over and engages the flap 1^b and has the opening 11 thereof disposed immediately over the tab 9 and reinforcing tab 12. The side walls of the spout 7 are slightly rounded, 55

as shown most clearly in Fig. 8 so that, when the spout is moved to the pouring position, the tab 9 engages the same and holds the spout in the pouring position. It is to be noted that the tab 9 extends a slight distance beyond the wall 3 of the box, as shown most clearly in Fig. 7. The reinforcing projection 12, being in contact with the tab 9, tends to reinforce the same and to urge it downwardly toward the spout. When the spout is in the non-pouring position, as shown in Fig. 7, the tab 9 is urged downwardly by the reinforcing tab 12 into engagement with the end of the spout to hold it in the non-pouring position. It will also be seen that the side wall of the container in which the spout is formed is made up of two layers 3 and 5, the layer 5 being the outermost layer, and the opening 10 provides a cut-away portion which is opposite the spout. The entire container is enclosed in a suitable label 20 or wrapper 13 which is provided with a readily frangible portion 14 which is disposed opposite the spout and overlies the cut-out portion 10. The end of the tab 9 projects outwardly a slight distance beyond the top edge of the spout 7 and holds the wrapper in spaced relation with respect to the spout. The opening in the side wall of the container opposite the spout 7 is covered only with the wrapper 13 and to obtain access to the spout, the thumb is inserted into this space and moved upwardly until it engages the projecting end of the tab 9 which facilitates the removal of that portion of the wrapper covering the spout. The tab 9 may then be lifted upwardly slightly against the tension of the reinforcing tab 12 to obtain access to the top edge of the spout. The spout may then be moved outwardly to the position shown in Fig. 8 at which time the tab 9 engages the rounded corners of the side walls of the spout and holds it in pouring position. It will therefore be seen that the tab 9 and the reinforcing tab 12 both tend to facilitate access to the spout. The reinforcing tab 12 places a slight tension on the tab 9 and tends to urge it downwardly and also prevents lifting the tab 9 too far so as to cause it to be bent out of place when the spout is not in use and to keep the carton closed except when the pouring spout is moved to pouring position.

It is also to be noted that the top of the spout, 50 when in the non-pouring position, is disposed at the intersection of a side wall and the top wall of the container which facilitates dispensing from the container all of the contents thereof. Another feature of the invention is that the side 55 wall of the container containing the spout is made up of two layers, the outermost layer being cut away opposite the spout to facilitate removal of the frangible portion of the label or wrapper.

It will now be clear that we have provided a 60 dispensing container which will accomplish the objects of the invention hereinbefore stated. It is to be understood that various changes may be made in the details of construction without departing from the spirit of the invention as the 65 embodiment of the invention herein disclosed is to be considered merely as illustrative and not in a limiting sense and the invention is limited only in accordance with the scope of the appended claims.

70 Having thus described our invention, what we claim is:

1. A paper container having a spout formed in one side wall thereof and integral therewith and movable to a pouring position, a flap forming a 75 part of the top wall of said container and having a

tab overlying said spout, a second flap overlying said first flap and having a reinforcing tab thereon which overlies said first mentioned tab and tends to urge the same downwardly toward said spout.

2. A paper container having a spout formed in one side wall thereof and integral therewith and movable to a pouring position, a flap forming a part of the top wall of said container and having a tab overlying said spout, a second flap overlying said first flap and having a reinforcing tab thereon which overlies said first mentioned tab and tends to urge the same downwardly toward said spout, said first mentioned tab projecting slightly beyond said spout when the spout is in 15 non-pouring position.

3. A paper container having a spout formed in one side wall thereof and integral therewith and movable to a pouring position, a flap forming a part of the top wall of said container and having a tab overlying said spout, a second flap overlying said first flap and having a reinforcing tab thereon which overlies said first mentioned tab and tends to urge the same downwardly toward said spout, a third flap overlying said second flap and 25 having a cut-out portion disposed over said first mentioned tab.

4. A paper container having a spout formed in one side wall thereof and integral therewith and movable to a pouring position, a flap forming a part of the top wall of said container and having a tab overlying said spout, a second flap overlying said first flap and having a reinforcing tab thereon which overlies said first mentioned tab and tends to urge the same downwardly toward said spout, said first mentioned tab projecting slightly beyond said spout when the spout is in non-pouring position, a third flap overlying said second flap and having a cut-out portion disposed over said first mentioned tab.

5. A paper container having a spout formed in one side wall thereof and integral therewith and movable to a pouring position, a flap forming a part of the top wall of said container and having a tab overlying said spout, a second flap overlying said first flap and having a reinforcing tab thereon which overlies said first mentioned tab and tends to urge the same downwardly toward said spout, said spout having side walls having 50 rounded ends adapted to be engaged by said first mentioned tab when the spout is moved to pouring position.

6. A paper container having a spout formed in one side wall thereof and integral therewith and movable to a pouring position, a flap forming a part of the top wall of said container and having a tab overlying said spout, a second flap overlying said first flap and having a reinforcing tab thereon which overlies said first mentioned tab and tends to urge the same downwardly toward said spout, and a wrapper enclosing said container and covering said spout and tabs and having a readily removable portion disposed over said spout, said first mentioned tab serving to 65 space the wrapper from said spout.

7. A paper container having a spout formed in one side wall thereof and integral therewith and movable to a pouring position, a flap forming a part of the top wall of said container and 70 having a tab overlying said spout, a second flap overlying said first flap and having a reinforcing tab thereon which overlies said first mentioned tab and tends to urge the same downwardly toward said spout, the side wall of said container 75

containing said spout having two layers, the outermost layer being cut away opposite said spout.

8. A dispensing container having a foldable spout formed in one wall thereof and integral therewith and movable to a pouring position, a flap overlying said spout and having a tab portion which extends beyond the upper edge of said spout when it is in non-pouring position and which is adapted to engage different portions of said spout to hold it in either the pouring or the non-pouring position.

10 9. A dispensing container having a foldable spout formed in one wall thereof and integral therewith and movable to a pouring position, a flap overlying said spout and having a tab portion which extends beyond the upper edge of said spout when it is in non-pouring position and

which is adapted to engage different portions of said spout to hold it in either the pouring or the non-pouring position, and means urging said tab portion downwardly toward said spout.

10 10. A dispensing container having a foldable spout formed in one wall thereof and integral therewith and movable to a pouring position, a flap overlying said spout and having a tab portion which extends beyond the upper edge of said spout when it is in non-pouring position 10 and which is adapted to engage different portions of said spout to hold it in either the pouring or the non-pouring position, said spout being disposed in a side wall of said container and said tab portion being disposed in the adjacent top 15 wall thereof.
